UNITED STATES PATENT OFFICE.

EMIL MÜLLER, OF DUSSELDORF, GERMANY, ASSIGNOR TO RHEINISCHE METALL-WAAREN-UND MASCHINENFABRIK, OF DUSSELDORF-DERENDRÖF, GERMANY, A CORPORATION OF GERMANY.

STALK-END LEVELER FOR SHEAF BINDERS.

Application filed June 9, 1924. Serial No. 718,868.

To all whom it may concern:

Be it known that I, EMIL MÜLLER, a citizen of Germany, residing at Dusseldorf, Germany, Fulicherstrasse 8, have invented **5** certain new and useful Improvements in or Relating to Stalk-End Levelers for Sheaf Binders, of which the following is a specification.

This invention relates to a stalk-end **10** leveler for sheaf binders used in connection with reaping or mowing machines, the object being to level the ends of the stalks previous to their being bound into sheaves.

These disadvantages are avoided in the **15** present invention. The improved stalk-end leveler of the present invention can be adjusted from the driver's seat during the operation of the sheaf binder, and the shield for leveling the stalk ends does not take part **20** in the swinging movement of the butt board, but may also be adjusted simultaneously from the driver's seat. Moreover, this leveling shield is still further adjustable for long and short stalks, in consequence where- **25** of the disadvantage of the space between the shield and butt board formed during the change of stroke is practically avoided. The leveling shield is also adapted to be **30** swung approximately into the plane of the butt board. The pivot for swinging the leveling shield is situated in the direction of the driving crank for the butt board.

In order to increase the extent of adjustment and to adapt the machine to all lengths **35** of stalk, according to the invention, any point of the stalk-end leveler may be positively connected with the adjustable binding table, in such a manner that the displacement of said binding table also causes **40** a corresponding displacement of the stalk-end leveler.

A simple form of construction may be **45** made by securing the bearing, in which the operating lever for the stalk-end leveler slides, to the binding table. The positive connection of the stalk-end leveler with the binding table necessitates a special guide for the leveling shield, in order to secure its correct position relatively to the butt board. For this purpose the shield of the stalk-end **50** leveler is connected not only to the control rod but is also connected yieldingly to a point on the elevator bearing or another

fixed point on the machine by means of an oscillating link or lever. **55**

Examples of constructions according to this invention are shown in the accompanying drawings in which:—

Fig. 1 is a side elevation of one form of sheaf binder. **60**

Fig. 2 shows part of the machine in plan view, the stalk-end leveler adjusted for long stalks being shown in full lines and in dotted lines for short stalks, without adjustment or displacement of the binding table for the **65** stalks. The dot and dash lines show the position of the binding table and the shield for smoothing the ends of short stalks.

Fig. 3 is a section on the line A—A of Fig. 2. **70**

Fig. 4 illustrates another form of a sheaf binder in side elevation.

Fig. 5 is a plan view of Fig. 4.

No claim is made herein for the structural **75** details of the form shown in Figs. 4 and 5, as such form constitutes the subject matter of a divisional application, Serial No. 24,128, filed April 18, 1925.

Referring first to Figures 1 to 3, the **80** stalk-end leveler is arranged upon the binding table B. The crank a is rotated by the shaft b and transmits a swinging movement to the butt board c. A guide d is linked at e to the butt board c and at its other end to a control rod f, the end of the latter being journaled on the elevator bearing g. The butt-board c is provided, on the side towards the binding-table B, with a toothed rail c₁ and bars c₂ in order to assist effectively the downward movement of the **85** stalks. **90**

The simultaneous adjustment of the butt board c and the leveling shield o is effected, in the form of construction according to Figs. 1 to 3, by means of the operating lever i to which is secured a plate p, in which is oscillatably mounted the pivot n for swinging the leveling shield o. The spring h of the leveling shield o is pivotally secured to the control rod f. The plate p of the operating lever i is connected with the spring h by means of the member k, said lever being situated within easy reach of the driver. **95**

The stalk end leveler is held in the desired position by means of notches m (Fig. **100**

1) provided in the lever *i*. The shield *o* is linked by means of the arms *o*₁ secured thereto, to the pivot *n* about which it turns, and is provided with a bracket *q* for guiding the spring *h*.

In order to effect an independent adjustment of the shield *o*, one side of the plate *p* is rigidly connected with the operating lever *i* whilst its other side is connected by means of the bolt *r* with the member *k*. The spring *h* slides during displacement in the bracket *q* and the shield *o* swings around the pivot *n* into the desired position. The adjustment is limited by a slot *s* in the plate *p* and the shield *o* is held in the desired position by clamping the member *k* to the plate *p* by means of a nut or screw *t*.

The working of the device is as follows:—

According to the length of the stalks, the stalk-end leveler is adjusted from the driver's seat into the desired position. The stalks are conveyed between the elevators to the upper edge of the binding table B where the stalk-end leveler and the packer-arms start their action. The toothed rail *c*₁ engages the stalks during the downward movement of the butt board *c* and is assisted by the bars *c*₂, in which action a partial leveling of the stalk-ends is effected. As soon as the stalk-ends are pressed against the leveling shield *o*, a further leveling takes place on account of the latter being at rest and not following the movement of the butt board *c*.

As soon as sufficient stalks have accumulated at the point where the binding takes place, the stalks are bound into a sheaf and the latter ejected by the ejector-arms of the binding arms. The stalk ends of the sheaf rest, until the sheaf is ejected, against the shield *o*, which, for this purpose is made specially long, so that it reaches to the lower edge of the binding table B. The lower edge of the shield *o* barely moves from the lower edge of the binding table B during the displacement of the stalk-end leveler in the direction towards the binding device, this being due to the positioning of the pivotal point of the shield *o*.

The stalk-end leveler enables the largest possible stroke to be made, in so far as the binding table B is adjustable in an inward and outward direction. A further advantage for short stalks is the possibility of the swinging of the butt board *c* so that all lengths of stalks may be dealt with without difficulty.

The disadvantage of a space between the butt board *c* and the shield *o*, which occurs during change of stroke in the stalk-end levelers used hitherto, is practically avoided by the positioning of the pivotal point *n* of the shield *o*, since the latter may be swung approximately into the plane of the butt board *c*.

In the form of construction shown in Figures 4 and 5, the adjustment or displacement of the stalk-end leveler and the binding table B is effected simultaneously. For this purpose a special bearing *u* is provided on a bent member *v* of the binding device *w*. The operating lever *i'* of the stalk-end leveler is slidably arranged in this bearing *u*. In addition thereto, the stalk-end leveler is adjustable from the driver's seat independently of the binding table B and the binding device *w* for longer or shorter stalks, for which purpose the operating lever *i'* is provided with notches *m'* for holding the stalk-end leveler in the bearing *u* in the desired position.

The stalk-end leveler consists in general of the butt board *c* and the leveling shield *o*. The butt board *c* causes the up-and-down movements for conveying the stalks from the upper edge of the binding table to the packer arms, whereas the leveling shield *o* remains stationary and serves as an abutment for the stalk-ends, and levels or smooths the latter until the sheaf is ejected. The control rod *f* is journaled at one end in the elevator bearing *g* and at its other end is connected with the butt board *c* by means of the link *d*, so that it is caused to follow its oscillations.

The leveling shield *o* is also journaled at the upwardly bent end of the control rod *f*, by means of the two arms *o*₁, while in the construction shown in Figs. 4 and 5 another arm *x* on the leveling shield *o* is connected to one arm of a double armed lever *y*, the latter being rockably mounted on the control rod *f*.

The other arm of the lever *y* is connected to a link *z* pivoted on the elevator bearing *g* beyond the journal of the control rod *f*.

It will be understood that the invention is capable of being carried out in various modifications, which come within the scope of the appended claims.

I claim as my invention:—

1. A stalk-end leveler for mowing and reaping machines, comprising a butt board; a driving crank connected to the butt board to oscillate the same; a leveling shield; a control rod connected with said shield; a link connected at opposite ends to the control rod and the butt board; and an operating lever for simultaneously adjusting said board and shield.

2. A stalk-end leveler for mowing and reaping machines, comprising a butt board; a driving crank connected to the butt board to oscillate the same; an adjusting lever; a plate secured to said lever to be moved thereby; a vertical pivot mounted in said plate and shiftable with the same; a leveling shield mounted on said pivot; connecting means between said shield and said plate to transmit the movement of said lever to

said shield and thereby swing the latter about the axis of said pivot; a control rod to which said connecting means is pivotally attached; and a link connection between 5 said control rod and the butt board.

3. A stalk-end leveler for mowing and reaping machines, comprising a butt board; a driving crank connected to the butt board to oscillate the same; an adjusting lever; 10 a plate secured to said lever to be moved thereby; a vertical pivot mounted in said plate and shiftable with the same; a leveling shield mounted on said pivot; a member

having an adjustable connection with said plate; a spring slidably engaged at one end 15 with said shield and fastened adjacent its other end to said member; a control rod to which the shield is pivotally attached at its said other end; and a link connection between said control rod and the butt board. 20

In testimony whereof I have affixed my signature in presence of two witnesses.

EMIL MÜLLER.
